UNITED STATES PATENT OFFICE.

HENRY R. LOOMIS, OF PROVIDENCE, RHODE ISLAND.

DESIGN FOR A PIN.

50,950.

Specification for Design. Patented June 19, 1917.

Application filed November 4, 1916. Serial No. 129,614. Term of patent 3½ years.

To all whom it may concern:

Be it known that I, HENRY R. LOOMIS, a citizen of the United States, and a resident of the city of Providence, in the county of Providence and State of Rhode Island, have invented a new, original, and ornamental Design for Pins, of which the following is a specification, reference being had to the accompanying drawings, forming part thereof.

Figure 1 is a front elevation of the head of a pin illustrating my new design.

Fig. 2 is a side elevation of the complete pin.

Jewels are mounted in the corners of the four-square portion, and at the ends of the vertically extended portion.

I claim:

The ornamental design for a pin, as shown and described.

HENRY R. LOOMIS.
